CLAIM

The ornamental design for a perforator for cigar or cigarette, as shown and described.

DESCRIPTION

FIG. 1 is a front elevational view of a perforator for cigar or cigarette showing my new design, the rear elevational view being identical thereto;

FIG. 2 is a top plan view of the perforator of FIG. 1; FIG. 3 is a bottom plan view of the perforator of FIG. 1; and

FIG. 4 is a side elevational view of the perforator of FIG. 1, the opposite side being identical.
